UNITED STATES PATENT OFFICE.

JOHN HAMELTON KEGANS, OF FONCINE, TEXAS.

DESIGN FOR A PLOWSHARE.

SPECIFICATION forming part of Design No. 31,490, dated September 5, 1899.

Application filed March 31, 1899. Serial No. 711,281. Term of patent 3 $\frac{1}{2}$ years.

To all whom it may concern:

Be it known that I, JOHN HAMELTON KEGANS, a citizen of the United States, residing at Foncine, in the county of Collin, in the State of Texas, have invented and produced a new and original Design for a Plowshare, of which the following is a specification, reference being had to the accompanying drawings, forming part thereof.

10 Figure 1 is a perspective view of a plow, showing my new design. Fig. 2 is a rear end elevation of the same. Fig. 3 is a plan view of the plowshare. Fig. 4 is a longitudinal section on line 4 4, Fig. 3. Fig. 5 is a trans-

15 verse sectional view on line 5 5, Fig. 3.

Similar letters of reference indicate similar parts in the several figures of the drawings.

As shown in the drawings the leading or material features of my design consist of a 20 substantially triangular plowshare or moldboard A, which when transversely viewed is

convexed; a wing B, disposed at an angle to the moldboard and having a comparatively straight lower edge and the upper edge of which combines with the adjacent edge of the 25 moldboard to produce an acute-angled recess C; in a moldboard when viewed in side elevation is concaved, and in an upwardly-disposed acutely-angled colter or blade D, that extends from the heel of the moldboard 30 to a short distance from the point E on the landside of the plow.

Having described my invention, what I claim as new, and desire to secure by Letters Patent, is—

35 The design for a plowshare, as herein shown and described.

JOHN HAMELTON KEGANS.
